UNITED STATES PATENT OFFICE.

EDWARD G. BUDD, OF PHILADELPHIA, PENNSYLVANIA, ASSIGNOR TO HALE-KILBURN METAL COMPANY, OF PHILADELPHIA, PENNSYLVANIA, A CORPORATION OF PENNSYLVANIA.

SEATING.

No. 884,711.

Specification of Letters Patent. Patented April 14, 1908.

Application filed March 23, 1907. Serial No. 364,195.

To all whom it may concern:

Be it known that I, EDWARD G. BUDD, a citizen of the United States, residing in Philadelphia, in the county of Philadelphia and State of Pennsylvania, have invented certain new and useful Improvements in Seating, of which the following is a specification.

This invention relates to seating adapted particularly for use as seat- and back-cushions for railway car seats, but susceptible of various and widely different uses.

The object of the invention is to provide such a seating which is not only of great strength, and capable of manufacture at comparatively low cost, but which is so constructed that it is fire proof.

In accordance with the invention, the seating consists of a metallic frame and a covering extending over and secured at its edges to the frame, this covering consisting of metallic strands closely interwoven. Such a covering in addition to being metallic, possesses the requisite flexibility, does not show wear, can be readily manufactured and is of an attractive appearance. If desired the several strands may be provided with convex upper faces and a coating of incombustible or other enamel may be applied thereto.

For convenience in weaving the metallic strands and also to facilitate attaching the covering to the metallic frame, it is important that strands be used made of metal which is rather soft and pliable and for this reason I have found it highly desirable to combine with such a metallic covering, suitable devices for preventing the covering from being dented, from sinking between the flat metallic springs commonly employed for supporting the covering of such seating, and from showing the marks of rivets or other uneven surfaces under the covering. For this purpose, I employ an open fabric of strips of spring-metal woven separately from the metal covering, and placed underneath the same. This spring fabric may be inclosed between two layers of textile fabric which may, if desired, be cemented thereto. With this I may combine a layer of asbestos cloth strengthened by having a fine woven-wire netting therein. With such a construction, the woven metallic covering is evenly supported in such a way that it will not show an uneven surface due to irregularities in the parts supporting it and after being depressed

at any point thereon, it will be immediately returned to its proper position; and this is accomplished without the use of felt and other upholstering material such as has been commonly employed in the seatings heretofore used and the use of which is very objectionable on account of its inflammable nature.

I have illustrated the preferred embodiment of my invention in the accompanying drawings in which

Figure 1 is a section of a portion of a cushion such as may be used as a seat-cushion for a car-seat, Fig. 2 is a plan view of a portion of the covering for the cushion, broken away to show the several layers thereof, Fig. 3 is a section through the covering, and Figs. 4 and 5 are views corresponding to Figs. 3 and 2, respectively, illustrating a modification.

Referring to these drawings, the cushion consists of a rectangular frame formed of four sheet-metal frame sections secured together at their ends. Each of these sections is pressed to provide a body-portion 1, an inwardly curled flange 2 at the upper edge thereof, an inwardly extending flange 3 at the lower edge, and a curled portion 4 at the inner edge of flange 3. Extending across between opposite members of the frame and secured at their ends thereto are a plurality of channeled metallic slats 5 each of which supports a line of spiral springs 6. Each line of springs 6 supports upon the upper end thereof a flat steel spring 7 the ends of which are turned downwardly and lie alongside the body-portions 1 of opposite frame members. The covering material of the cushion overlies the flat springs 7 and at its edges is carried down along the body-portions of the frame members, under the flanges 3 thereon and around the curled portions 4. Metallic clamps 8 are gripped about the edges of the covering material and the curled portion 4 to hold the covering tightly to the frame.

The covering of the cushion consists of a fabric 9 of metallic strands closely interwoven. Any suitable weaving of these strands may be employed as for instance a square weave or the twill weave illustrated in the drawings. The strands of the fabric 9 may have their upper faces slightly convex and the upper surface of the covering may have a coating of enamel applied thereto. In order to secure the requisite flexibility of

the covering and to facilitate weaving the strands and securing the covering upon the frame, the strands of the covering 9 are made of soft, pliable metal, and I therefore 5 combine with this woven material means for preventing it from taking a shape other than that desired. This consists preferably of an open fabric 10 of strips of spring-metal woven together, as shown in Fig. 2. The strips of 10 this fabric may be secured together at the points where they cross each other by galvanized tinning, soldering or other suitable means to prevent them from moving relatively. The fabric 10 underlies the central 15 portion of the woven covering 9 and may be of such size that its edges extend down along the body-portions 1 of the frame-members or not, as desired. The fabric 10 of strips of spring-metal is inclosed between two layers 20 11 and 12 of a textile fabric, as canvas duck, and is preferably cemented thereto, this construction being illustrated in Figs. 2 and 3. In some cases I have found it desirable to combine with the spring fabric and the layers 25 of textile fabric a layer of asbestos cloth 13, as shown in Figs. 4 and 5, and this cloth may have a fine woven-wire fabric therein, as shown at 14, Fig. 5. When this layer of asbestos cloth is employed, it is preferably 30 placed between the spring fabric 10 and one of the layers of textile fabric 11 and 12. The cushion constructed as above described is fire proof as practically all of the parts are of metal or other incombustible 35 material. The covering, though constructed of metal, possesses the requisite flexibility and resiliency, the latter being secured not only by the spiral springs 6 and flat springs 7, but also by the spring fabric 10. The use of 40 felt and other inflammable upholstering material, such as have been commonly employed in cushions heretofore, is thus avoided. The spring fabric 10 and the layers of textile fabric combined therewith also serve 45 the important function of preventing the woven metallic covering 9 from becoming dented, from sinking in the spaces between the flat springs 7, from showing marks of rivets or other uneven surfaces on the underlying structure, or from in any other way being bent and taking a set out of the desired shape.

I do not wish to be understood as limited to a covering consisting of the parts herein 55 described arranged as set forth, as various changes in these respects may be made. The spring fabric separate from the covering but yieldingly supporting the same may be employed without the other layers of the covering or either the canvas duck or the asbestos cloth layers may be omitted and modifications 60 may be made with respect to the number of the layers carried around the flange at the bottom of the frame-members. All such 65 modifications I consider within the scope of

my invention and I aim to cover them by the terms of the appended claims.

Having described my invention what I claim as new and desire to secure by Letters-Patent of the United States is:

1. In seating, the combination of a covering formed of flattened metallic strands closely interwoven forming the surface material of the seating and a fabric of flat spring-metal strips separate from said covering and underlying the same, substantially as described. 75

2. In seating, the combination of a covering formed of flattened metallic strands closely interwoven forming the surface of the seating and a fabric of flat spring-metal strips separately formed and underlying the same, the strips crossing each other being secured together, substantially as described. 80

3. In seating, the combination of a metallic frame consisting of sheet-metal frame-sections secured together at their ends, a covering extending over and secured at its edges to said frame consisting of flattened metallic strands closely interwoven said covering forming the surface material of the seating, and a fabric of flat spring-metal strips formed separate from said covering and underlying the same, substantially as described. 85

4. In seating, a covering formed of flat metallic strands closely interwoven and a textile fabric and a fabric of flat spring-metal strips underlying the same, substantially as described. 95

5. In seating, a covering formed of flattened metallic strands closely interwoven, and a fabric of flat spring-metal strips inclosed between layers of textile fabric underlying said covering, substantially as described. 100

6. In seating, a covering formed of flattened metallic strands closely interwoven, a fabric of flat spring-metal strips underlying the same, and a layer of canvas duck on either side of said spring-metal fabric and cemented thereto, substantially as described. 105

7. In seating, a covering formed of woven metallic strands, and a fabric of spring-metal strips and a layer of asbestos cloth underlying said covering, substantially as described. 110

8. In seating, a covering formed of woven metallic strands, a fabric of spring-metal strips underlying the same, and a layer of textile fabric and a layer of asbestos cloth associated with said spring-fabric, substantially 115 as described. 120

9. In seating, a covering consisting of woven metal strands, and, underlying the same, a fabric of spring-metal strips and a layer of asbestos cloth inclosed between layers of textile fabric, substantially as described. 125

10. In seating, a frame consisting of metallic frame-sections secured together at their ends, a covering of flattened metallic strands closely interwoven extending over and se- 130

cured at its edges to said frame, a fabric of flat spring-metal strips underlying the central portion of said covering and a textile fabric associated with said spring-metal fabric, substantially as described.

11. In seating, the combination of a frame consisting of sheet-metal frame-sections secured together at their ends, a covering consisting of metallic strands closely interwoven extending over and secured at its edges to said frame, a fabric of spring-metal strips underlying the central portion of said covering, and a layer of asbestos cloth associated with said spring-metal fabric, substantially as described.

12. In seating, the combination of a frame

consisting of sheet-metal frame sections secured together at their ends, a covering consisting of flattened metallic strands closely interwoven extending over the top and sides 20 of said frame and forming the surface material of the seating, its edges being carried under and secured to said frame sections, and a fabric of spring-metal strips underlying the central portion only of said covering, substantially as described. 25

Corrections in Letters Patent No. 884,711.

It is hereby certified that in Letters Patent No. 884,711, granted April 14, 1908, upon the application of Edward G. Budd, of Philadelphia, Pennsylvania, for an improvement in "Seating," errors appear in the printed specification, requiring correction, as follows: In line 80, page 2, after the word "surface," the word *material* should be inserted, and in line 95, same page, the word "flat" should read *flattened*; and that the said Letters Patent should be read with these corrections therein that the same may conform to the record of the case in the Patent Office.

Signed and sealed this 28th day of April, A. D., 1908.

cured at its edges to said frame, a fabric of flat spring-metal strips underlying the central portion of said covering and a textile fabric associated with said spring-metal fabric, substantially as described.

11. In seating, the combination of a frame consisting of sheet-metal frame-sections secured together at their ends, a covering consisting of metallic strands closely interwoven extending over and secured at its edges to said frame, a fabric of spring-metal strips underlying the central portion of said covering, and a layer of asbestos cloth associated with said spring-metal fabric, substantially as described.

12. In seating, the combination of a frame

consisting of sheet-metal frame sections secured together at their ends, a covering consisting of flattened metallic strands closely interwoven extending over the top and sides 20 of said frame and forming the surface material of the seating, its edges being carried under and secured to said frame sections, and a fabric of spring-metal strips underlying the central portion only of said covering, substantially as described. 25
